UNITED STATES PATENT OFFICE.

SETH D. BOWKER, OF KANSAS CITY, MISSOURI; MARTIN D. WOOD
ADMINISTRATOR OF SAID BOWKER, DECEASED.

UTERINE CURETTE.

SPECIFICATION forming part of Letters Patent No. 687,112, dated November 19, 1901.

Application filed October 4, 1900. Serial No. 32,015. (No model.)

To all whom it may concern:

Be it known that I, SETH D. BOWKER, M. D., a citizen of the United States, and a resident of Kansas City, in the county of Jackson and 5 State of Missouri, have invented new and useful Improvements in Uterine Curettes, of which the following is a specification.

My invention is an instrument offered to the medical profession which can be opened 10 to fit the internal shape of the uterus after being introduced therewith through the neck of the uterus.

The object of the instrument is to clean out the inside of the uterus and remove any 15 diseased surface or adhered afterbirth or to remove fungous growths.

With this object in view my invention consists in the novel construction and arrangement of parts, which will be hereinafter 20 described, and pointed out in the claim.

Referring to the accompanying drawings, Figure 1 is a view of the instrument with the spring-blades closed, showing one position of the blades when open in dotted lines. Fig. 2 25 is a longitudinal sectional view of the same, showing the central rod partly in section. Fig. 3 is a transverse sectional view taken on the line *a b* of Fig. 2. Fig. 4 is a detail view.

30 The instrument comprises the outer sleeve or casing 2, the externally-threaded tube 3, lying within the casing, the central rod 4, and the spring-blades 5. The outer end of rod 4 is drilled out, as shown in Fig. 2, so as to 35 leave a thin tubular portion 6, and beyond the bottom of this portion a smaller perforation is drilled and tapped for the screw 7.

The blades 5, preferably four in number, are made of watch-spring steel or the like, 40 and the "temper" is withdrawn from their ends, so that the ends can be bent for connection to rod 4 and tube 3. The incurving portions of the outer ends of the blades pass through notches 21 in the ends of the tubular 45 portion 6 and are then curled, substantially as shown in Fig. 2, with their ends projecting into or through perforations 17. The notches 21 are deep enough to permit some movement of the curved portions of springs while the 50 screw 7 is tight. While I prefer this manner of attaching the blades to the end of the rod,

I do not wish to limit myself to the exact construction shown. The opposite ends of blades 5 are bent inwardly and are held loosely in perforations in the end 8 of tube 3. The 55 springs are normally prevented from disengagement from tube 3 by the end of the casing 2. The casing 2 is made from two sections, which are permanently secured to the intermediate bushing 9, which has internal 60 screw-threads engaging the external threads on tube 3. It will thus be seen that relative longitudinal motion between tube 3 and casing 2 may be had by holding the handle 10, which is rigidly secured to tube 3, and rotating 65 the casing 2 between the thumb and finger. The knurled flange 12 is a convenience for this purpose, but is not essential.

The outer end of rod 4 passes slidingly 70 through a perforation in handle 10 and is provided with screw-threads for engagement with the thumb-nut 14. A spline-groove 15 is formed in the threaded portion of rod 4, and this groove is engaged by a pin 16, tightly secured in the handle 10, for preventing relative 75 rotation between the rod 4 and tube 3. Rotation of thumb-nut 14 in one direction draws the rod 4 into the tube 3, and thereby spreads or curves the spring-blades 5 to any extent 80 that may be required. The dotted lines in Fig. 1 indicate approximately, if not exactly, one of the curvatures into which the blades 5 may be held. The thumb-nut bearing against the handle 10 holds the blades in any required 85 position. The movement of the casing 2 around the blades provides a further adjustment of the blades to different-sized cavities, as it will be clearly understood that the casing 2 can be advanced until it covers a greater portion of the length of the blades, or it may 90 be set in any intermediate position, so that when the rod 4 is retracted by thumb-nut 14 the only portion of the blades that can curve outwardly is the portion between the screw 7 and the end of the casing 2. 95

The instrument is quickly and easily cleaned by first moving the casing 2 toward the handle 10, so as to release the blades 5 from the perforations in the end of tube 3, and then removing the thumb-nut 14 from the rod 100 4. The rod may then be withdrawn from the tube, and the casing 2 may be entirely sep-

arated from the tube by rotating it until the threaded bushing 9 passes off the end of the tube. To assemble the instrument after clearing, the casing 2 is screwed back on the tube 3 nearly to the handle, so as to leave the end of the tube exposed. The rod 4 is inserted in the perforations in the tube 3. A small rubber band or washer placed around the blades will hold the blades in position until the casing is turned to cover these ends of the blades, and the same washer if pushed into the end of the casing around the springs will exclude blood or other fluid to some extent from the casing. When the instrument is withdrawn from the uterus, the substances detached by the blades 5 are caught by the blades and removed.

Having now fully described my invention,

what I claim as new, and desire to secure by Letters Patent of the United States, is—

In a uterine curette, a cylindrical rod, an externally-threaded tube surrounding a portion of the rod, a spline-groove in the rod, a pin secured in the tube engaging said groove, a sleeve surrounding a portion of said tube, and internal screw-threads located between the ends of said sleeve and engaging the external threads of said tube, substantially as described.

In testimony whereof I affix my signature in the presence of two witnesses.

SETH D. BOWKER.
